UNITED STATES PATENT OFFICE

2,519,082

DUST FILTER FOR VACUUM DRIERS

Gustie Stevenson, Philadelphia, Pa., assignor to
F. J. Stokes Machine Company, a corporation
of Pennsylvania

Application April 17, 1947, Serial No. 742,161

5 Claims. (Cl. 183—51)

1

This invention relates to dust filters to be applied especially for the purpose of removing dust or other particles from the vapors or gases drawn from a vacuum dryer and for preventing such particles from reaching the vacuum pump.

My dust filter is of the type to be mounted upon a vapor outlet of the dryer located at the top thereof and positioned so that accumulated dust or particles may be returned to the dryer by shaking or agitating the filter. For this purpose, the filter unit of my filter is formed as a bag and is mounted in inverted position.

An object of my invention is to devise a filter construction in which the filtering unit may be easily removed for repairs or for replacement of a new unit.

A further object of the invention is to devise an arrangement for vibrating the filter unit while the unit is mounted within a vacuum-tight casing.

Other objects will become apparent from the following description taken in connection with the accompanying drawing, the single figure of which is a side view of the filter construction, the left half of the view being shown in section and the right half in elevation.

Referring to the drawing, my improved filter involves a tubular casing 1 having an annular flange 2 at its lower end by which the casing is mounted upon the vapor outlet 3 of the dryer, not shown. The outer portion of the flange 2 is used to make a vacuum-tight joint with a flange on outlet 3, and the portion of the flange 2 extending inwardly beyond the wall of casing 1 serves as a support for the filter unit. Casing 1 preferably is in the form of a cylinder, although it might have other shapes.

The upper end of casing 1 is closed by a removable cover or closure formed of a plate 4 seated on an annular flange 5 at the upper end of the casing 1, with a sealing ring 4a interposed; the ring 4a may be formed of rubber or other suitable material and preferably has a locking portion extending into an annular groove formed in the cover plate 4. The cover plate is hinged to the casing 1 by means of an arm 6 pivotally connected to a bracket 7 mounted on the casing 1, and the plate 4 is pivotally connected to the arm 6 by means of a pair of brackets 4b. The arm 6 extends entirely across the cover plate 4 from the bracket 7 and the outer end of the arm is bifurcated to receive an eye-bolt 8 pivotally mounted upon a bracket 9 carried by the casing 1. A hand wheel 10 has threaded engagement with the upper end of the eye-bolt 8, and by means of this construction the cover plate 4 may be tightly clamped in position to seal the upper end of the filter casing. The arm 6 extends to the right of bracket 7 and may be provided with a counter-weight 6a mounted for adjustment thereon.

The filter casing is provided with an outlet 11 formed in its vertical wall and extending horizontally from the casing near the upper end thereof.

2

The lower portion of the filter casing 1 is provided with a steam jacket 12 through which steam is passed by means of an inlet connection 12a at the top of the jacket and an outlet connection 12b at the bottom thereof.

The filter unit is formed of a filter element in the form of a fabric bag having a supporting frame, and is supported within the casing 1 on the flange 2. The frame for supporting the filter bag includes a short cylindrical ring 13 having an external annular flange 14 secured to the lower end thereof and which is seated upon the inner part of flange 2 of the casing 1 with a ring of sealing material 15 interposed. Preferably, the sealing ring 15 has a locking portion extending into an annular groove formed in the lower face of the flange 14. A number of vertical rods 16 spaced about the ring 13 have their lower ends secured to the ring 13 in any suitable manner, preferably by welding the ends of the rods to the inner surface of the ring 13. The rods 16 preferably are formed of tube or pipe stock, with the ends flattened as shown in the drawing. An annular ring 17 formed of an angle section consisting of a vertical flange and a horizontal flange is suitably secured to the upper ends of the rods 16, as by welding. The lower ends of certain of the rods 16 may be extended downwardly below the flange 14 and turned inwardly as shown at 16a to serve as guides for centering the flange 14 on the flange 2. Any other construction for centering the flange 14 on its seat may be used.

The filter bag 18, preferably formed of canton flannel with the nap arranged inside of the bag, is supported by the frame just described, in an up-side down position. The neck of the bag is securely clamped around the outside surface of the ring 13 by means of a clamping band 18a.

The bag supporting frame is securely clamped on the seating flange 2 by means of a clamping structure now to be described. An annular clamping head in the form of an angle ring 19 fits over the upper end of the filter unit and is provided with a number of radially extending arms 19a secured to the outside thereof. These arms are provided with slots in the side edges thereof for receiving the upper ends of four long eye-bolts 20 which are anchored at their lower ends to studs 21 mounted on the inside of casing 1 near the lower end thereof. The bolts 20 are provided with clamping nuts 20a threaded on their upper ends, and it is desirable to provide some means for preventing removal of these nuts while permitting adjustment downwardly to clamp the filter unit in position. The clamping ring 19 is provided with a pair of handles 22, 22 located on opposite sides thereof and by which the ring, after loosening of the nuts 20a, may be removed from the casing 1 by rotating the ring until the arms 19a disengage the bolts 20, and then lifting the clamping ring vertically upward through the open end of the casing. It is not necessary to twist or rotate the ring 19 to dis-

engage it from bolts 20, since the upper ends of the bolts may be swung out of engagement with arms 19a. After the clamping ring 19 has been removed, the filter unit may also be removed through the upper end of the casing 1 for replacement of a new unit or a new bag.

It will be understood that the outlet 3 of the dryer is a vertical outlet positioned at the top of the dryer so that the filter bag 18 is positioned directly above the dryer. Vapors or gases drawn from the dryer pass upwardly through the open lower end of the bag 18 and through the sides of the bag or through the central part of the bottom thereof, and then pass out through the outlet 11 of the filter casing leading to the vacuum pump. Any dust or other particles carried by the vapors or gases are deposited on the inside surface of the bag 18, and when the deposit becomes sufficiently thick to drop off by gravity, it falls directly back into the dryer.

In order to facilitate removal of the deposited particles from the dust bag without breaking the vacuum on the dryer, provision is made for vibrating the filter unit from a source of power located outside of the filter casing. For this purpose, any suitable form of vibrator represented at 24 may be mounted on the outside of the casing 1 opposite the upper end of the filter unit, and vibrations may be transmitted to the clamping ring 19 or to any of the eye-bolts 20, by means of a rod 25 passing through a suitable stuffing box 26 provided in the wall of the casing. The driving rod 25 may be connected to the ring 19 or to one of the eye-bolts 20 by a releasable connection, or it may be arranged so that the end of the rod merely comes in contact with one of these elements in a manner to vibrate it. The eye-bolts 20 constitute tension elements or clamping the filter unit on the seating flange 2 of the filter casing. Due to the fact that these tension rods 20 are relatively long, these rods and the upper end of the filter frame are free to be vibrated by the vibrator 24, and thus remove the deposited material as it accumulates. It will be understood that the supporting frame for the filter bag is of a resilient construction to permit the vibration just described.

It is preferred that all parts of the filter exposed to the vapors or gases be constructed of stainless steel or other non-corrosive metal.

I claim:

1. A filter construction comprising a vertical tubular casing open at both ends and having an annular internal flange near the lower end, a removable cover for the upper end of said casing, a resilient annular frame insertable through the upper end of said casing and seated on said annular flange, an inverted filter bag surrounding said resilient frame, means for releasably clamping said frame to said annular flange comprising a clamping head removably supported on the upper end of said frame, a plurality of tension members spaced about said clamping head between said bag and said casing and being connected at their upper ends to said head and at their lower ends to fixed points of support adjacent the lower end of said annular frame, a rod extending through the wall of said casing adjacent the upper end of said frame and being mounted for longitudinal reciprocation, and a connection from the inner end of said rod to said clamping head for imparting lateral vibrations to the upper end of said frame through said clamping head.

2. A filter construction according to claim 1

wherein said annular frame comprises an annular ring seated on said internal flange, a plurality of vertical members spaced about said ring and secured to said ring at their lower ends, and a ring secured to the upper ends of said vertical members.

3. A filter construction comprising a vertical tubular casing open at both ends and having an annular internal flange near the lower end, a removable cover for the upper end of said casing, a resilient annular frame insertable through the upper end of said casing and seated on said annular flange, means for clamping said frame upon said annular flange comprising a clamping head carried on the upper end of said frame and a plurality of tension members spaced about said head between said frame and said casing and connected to fixed points of support near the lower end of said frame, the upper ends of said tension members passing through holes in said clamping head, and releasable clamping devices carried on the upper ends of said tension members for clamping said frame on said flange.

4. A filter construction according to claim 3 and including a rod extending through the wall of said casing adjacent the upper end of said frame and connected to one of said tension members below said clamping head, said rod being mounted for longitudinal reciprocation to impart lateral vibration to said frame through said clamping head.

5. A filter construction comprising a vertical, cylindrical casing open at both ends, an annular plate secured to the lower end of said casing and providing an external coupling flange and an internal annular flange at the lower end of said casing, a removable cover for the upper end of said casing, a cylindrical filter unit insertable through the open end of said casing and having its lower open end seated upon said internal flange and having its upper end closed, means for clamping said filter unit in position on said internal flange comprising a clamping head carried by the upper end of said filter unit, a plurality of vertical clamping rods arranged around said filter unit within the space between said unit and said casing, said clamping rods being connected at their lower ends to fixed points of support adjacent the lower end of said filter unit and having their upper ends extending through holes formed in said clamping head, removable clamping devices carried by the upper ends of said clamping rods and pressing said clamping head against the upper end of said filter unit, and a vibrator rod secured to one of said clamping rods near the upper end thereof and extending horizontally through the wall of said casing for imparting lateral vibrations to the upper end of said filter unit.
